UNITED STATES PATENT OFFICE.

JOHN T. LEE, OF MINNEAPOLIS, MINNESOTA.

VETERINARY CUTTING-FORCEPS.

SPECIFICATION forming part of Letters Patent No. 427,772, dated May 13, 1890.

Application filed November 12, 1889. Serial No. 330,038. (No model.)

To all whom it may concern:

Be it known that I, JOHN T. LEE, a citizen of the United States, residing at Minneapolis, in the county of Hennepin and State of Minnesota, have invented new and useful Cutting-Forceps, of which the following is a specification.

The object of this invention is to provide a pair of cutting-forceps for cutting the incisors of horses, and to accomplish the same in such a manner as to make a clean cut and avoid breaking the enamel adjacent to the cut, and, furthermore, to provide a pair of forceps so constructed as to be simple and cheap and to lend the greatest amount of leverage for operating the cutting-bar.

With these general objects in view the invention consists in certain features of construction hereinafter specified, and particularly pointed out in the claim.

Referring to the drawings, Figure 1 is a perspective of a pair of forceps constructed in accordance with my invention. Fig. 2 is a detail in longitudinal section of the upper end 25 of the same. Fig. 3 is a detail of the bar-operating lever. Figs. 4 and 5 are details in perspective of modifications.

Like numerals of reference indicate like parts in all the figures of the drawings.

In practicing my invention I provide two sections or members 1 and 2, the former being designated as a "movable" or "hinged" section and the latter as the "stationary" section. The stationary section 2 comprises a rear handle portion 3, which terminates in a perforated shoulder 4, and beyond the same there is formed a head 5, the extremity of which is curved to form a jaw 6, terminating in a cutting-head 7. Between the shoulder 4 and the jaw there is secured to or formed upon the section a strap or guide 8, forming a passage in which is mounted the cutter-bar 9, the upper end of which is in line with the cutter 7 and is beveled to form a cutting-edge 10. The lower end of the cutting-bar is slightly reduced, forming opposite shoulders 11, and below the shoulders and at the lower end of the bar is formed an offset lug or projection 12, perforated as at 13. The section 1, which is 45 the pivoted or hinged section, also terminates

in handles 3 at one end, and at its upper end is provided with a concaved opening or recess 13^a for the reception of the perforated shoulder or lug 4 upon the opposite section. Projecting at a right angle from the upper end 55 of the section 1 and at each side thereof is a strap or arm 14, perforated as at 15 and 16. Through the perforation 15 and the perforation in the shoulder or lug 4 there is inserted a pin 17, by which the section 1 is pivotally 60 connected to the section 2. Through the opening 16 and the opening in the lug 12 there is inserted a second pin 18, which pivotally connects the forward ends of the straps with the lower end of the cutter-bar.

The cutting-edges of both the jaw and the cutter-bar are preferably slightly concave, as shown, for the purpose of adapting the two conjointly to the natural contour of the incisor. If desired, and as shown in Fig. 4, the 70 cutting-edges may be disposed at a right angle to that shown in Fig. 1, and, as also shown by the modification, Fig. 5, said edges may be serrated in order to increase the cutting efficiency of the same.

The operation of my invention will be readily understood by those conversant with the treatment of horses, in that it is simply necessary to spread the handles and introduce the cutters over the incisor and then lower 80 the pivoted handle.

Having thus described my invention, I claim—

In an instrument of the class described, the combination, with the section 2, terminating at one end in a handle 3 and at its opposite end in a curved head 5, the extremity of which is beveled to form a fixed cutter below the head and upon the opposite side provided with an outwardly - projecting perforated 85 curved bearing-shoulder 4 and at its front face with a fixed guide 8, of the sliding cutter 9, mounted in the guide beveled at its upper end, as at 10, and having its lower end terminating in the shoulder 12, forming a stop for 95 the upward movement of the cutter by coming in contact with the lower end of the guide and perforated, as at 13, and the section 1, terminating at one end in the handle 3 and at the upper end provided with the curved 100

recess 13^a, to bear upon the shoulder 4, and the opposite straps 14, having their rear ends rigid with the section and forming end walls for the recess, and having their forward ends 5 pivoted, as at 18, to the perforated shoulder 12 of the movable cutter 9, and the pivot 17, passed through the shoulder and forward ends of the straps, substantially as specified.

In testimony that I claim the foregoing as my own I have hereto affixed my signature to in presence of two witnesses.

JOHN T. LEE.
